UNITED STATES PATENT OFFICE.

JOANNY GABRIEL BRUYÈRE, OF LYON, FRANCE.

AUTOMATIC BRAKING MECHANISM FOR THE FEED ROLLER OF WIRE DRAWING MACHINES.

Application filed February 20, 1926, Serial No. 89,636, and in France March 28, 1925.

This invention relates to automatic braking mechanism for the feed roller of wire drawing machines.

According to the invention the wire on emerging from the dies passes under a roller mounted on one end of a bell crank lever and tensioned either by the weight thereof or by a spring, the pivoting of the bell crank lever should the wire break either in front of or behind the dies applying a brake which stops the rotation of the feed drum.

Waste is thus avoided and the risk of deterioration of the dies due to the irregular passage of the wire is diminished and the entanglement of the severed ends in the press is avoided.

The invention will be described with reference to the accompanying drawings.

Fig. 1 is a side elevation.

Fig. 2 is an end elevation.

Fig. 3 is a diagrammatic elevation showing the position of the parts when a break occurs.

Fig. 4 is a diagrammatic end elevation the break being released.

The wire *a* unwound from a drum *b* passes over a table *c* and then between the dies *d* of a rolling mill which draws it into a wire *e*, being finally wound on to a drum *f*.

According to the invention on emerging from the rollers the drawn wire *e* passes round a roller *g* carried by one of the arms of a bell crank lever *h* freely pivoted on a rod *i* and affixed by a spring *j* to the frame, then over a stationary roller *k* and a fixed roller *l* and is finally rolled on to a drum *f*.

The second arm of the bell crank lever *h* is affixed through the rod *m* to the end of a lever *n* pivoted on a bracket *o* and against which the brake operating rod *p* is held by the spring *q*.

A lever *r* pivoted at *s* is pivoted to the other end of the rod *p*, the lever *r* being formed with an eye *t* in which a finger *u* mounted on a shaft *v* engages during the normal running of the machine.

This shaft *v* carries a brake shoe *w* and a spring *x* which tends to turn the shaft in the direction of the arrow *x*.

The feed drum *b* is screwed on to a shaft *y* which is of conical shape to accommodate drums of varying diameters and hold them securely. At the right hand side of the brake shoe *w* a brake drum *z* is mounted on the shaft *y* which rotates in a fixed bearing

2 and an adjustable bearing 3 mounted on pedestals 4. In order to ensure a suitable feed the shaft *y* is continually braked by a shoe 5 bearing on the drum *z* the pressure being adjustable by means of a screw 6. 60

If the drawn wire *e* or the wire *a* breaks at any point the lever *h*, which is held in the raised position by the drawn wire *e*, is lowered by the spring *j* and pivots in the direction of the arrow 7, raising the end of the lever *n* which slides out of contact with the rod *p*. 65

The spring *q* draws the rod *p* horizontally and pivots the lever *r* about the point *s*; the eyelet *t* releases the finger *u* and the shaft *v* being freed is rotated by the spring 8 and applies the shoe *w* against the drum *z*, stopping the drums *b*. 70

If the breakage occurs between the drum *b* and the rollers *d* these latter hold the length of wire between them and the point of breakage; when this has passed they rotate empty. 75

If the breakage occurs between the rollers *d* and the drum *f* the stoppage of the drum *b* since the rollers *d* continually rotate, places a great tension on the wire *a* which therefore breaks between the drum *b* and the rollers and the first case has again taken place. 85

The waste is therefore reduced to a minimum since as soon as the breakage occurs no more wire is unwound. This eliminates the risk of entanglement of the severed ends of the wire in the machine and deterioration of the dies of the drawing press by irregular passage of the wire. 90

What I claim as my invention and desire to protect by Letters Patent is:—

1. Automatic braking mechanism for the feed roller of wire drawing machines comprising in combination a bell crank lever pivoted to the frame, a roller mounted on one arm of the bell crank lever under which the wire passes, a rod pivotally connected to the second arm of the bell crank lever, a lever pivoted to the frame and to the lower end of said rod, a spring loaded rod engaged by the lever, a rocking lever pivoted about its centre to the frame, one end of said rocking lever being pivotally connected to said rod, a spring loaded transverse shaft, a finger projecting therefrom to engage an eyelet in the upper end of the rocking lever, a brake shoe on the transverse shaft and a 105
110

brake drum on the feed roller engaged thereby on the rotation of the transverse shaft.

2. Automatic braking mechanism for the feed roller of wire drawing machines comprising in combination a bell crank lever pivoted to the frame, a roller mounted on one arm of the bell crank lever under which the wire passes, a spring connected between the arm of one bell crank lever and the frame, a rod pivotally connected to the second arm of the bell crank lever, a lever pivoted to the frame and to the lower end of

said rod a spring loaded rod engaged by the lever, a rocking lever pivoted about its centre to the frame, one end of said rocking lever being pivotally connected to said rod, a spring loaded transverse shaft, a finger projecting therefrom to engage an eyelet in the upper end of the rocking lever, a brake shoe on the transverse shaft and a brake drum on the feed roller engaged thereby on the rotation of the transverse shaft.

In witness whereof I affix my signature.

JOANNY GABRIEL BRUYERE.
